UNITED STATES PATENT OFFICE.

CHARLES FREDERICK BRAND, OF WHEELING, WEST VIRGINIA.

HOT-AIR HEATER.

SPECIFICATION forming part of Letters Patent No. 746,002, dated December 8, 1903.

Application filed March 5, 1903. Serial No. 146,289. (No model.)

To all whom it may concern:

Be it known that I, CHARLES FREDERICK BRAND, a citizen of the United States of America, and a resident of Wheeling, county of Ohio, and State of West Virginia, have invented certain new and useful Improvements in Hot-Air Heaters, of which the following is a specification.

My invention relates to hot-air heaters, and more particularly to a heater for an open grate or stove where gas is used, which is so constructed as to assure a maximum radiation of heat with a minimum supply of fuel.

The object of the invention is to provide a new and improved heater which is simple, inexpensive, durable, and efficient for the purposes for which it is designed.

A further object of the invention is to provide a device of the character mentioned which will readily produce much more heat than is ordinarily secured from an ordinary open gas-grate.

Further objects of the invention will be made apparent as further progress is made with this specification.

In describing my invention in detail reference is herein had to the accompanying drawings, forming a part of this specification, in which—

Figure 1 is a front plan view of an open gas-grate equipped with my invention. Fig. 2 is a longitudinal section of the same, showing my invention in cross-section. Fig. 3 is a perspective view of the radiating-box. Fig. 4 is a similar view of the deflector for the radiating-box. Fig. 5 is a longitudinal section of an elbow. Fig. 6 is a similar section taken on the line 6 6 of Fig. 5.

In said drawings like reference-numerals designate like parts throughout the several views.

Referring to said drawings, 1 indicates an ordinary open fireplace or grate equipped with the ordinary perforated gas-burner 2, to which the gas is supplied through the pipe 3 and the mixer 4.

5 indicates a horizontal pipe which may be either sheet metal or stiff iron, preferably the former, said pipe being located directly over said perforated burner 2. Joined to said hori-

zontal pipe 5 at each end by means of elbows 6 is an upright metal pipe 7, said upright pipes standing close to or against the edge of the grate and having their upper ends opening into a rectangular box 8, which box is mounted on the pipe ends. Opening into the horizontal pipe 5, preferably at points midway in its length, is one or more inlet-tubes 9, the lower ends of which are bent outward, as shown, and have funnel-shaped openings 60 or air-inlets 10.

The rectangular box 8 is open at its front side, and seated therein is a deflector, substantially as shown in Fig. 4, which is preferably formed of one continuous piece of metal 11, having its corners turned down to form supports 12. The object of said deflector is to throw or deflect the heat which passes up into the box 8 forward. Suitably supported in front of the box 8 is a perforated sheet-metal radiator 13, into which the heat passed upward into the box 8 is deflected and from which it is permitted to escape into the room.

As shown in the drawings, the horizontal pipe 5 and the upright pipes 7 are constructed of a plurality of pieces adapted to telescope one within another in order that the device may be adjusted to fit different-sized grates.

The horizontal pipe 5 may be, and is preferably, covered with a layer or thickness of asbestos paper 14, the object of which is to prevent the burning up of the said pipe from the flame arising from the burner 2. This may be coated over, as may also the upright pipes 7, with asbestos fiber, thus completely hiding and protecting said pipes.

My invention operates substantially as follows: The flame from the burner 2 rises and divides on each side of the pipe 5, heating said pipe, and consequently the air therein. The hot air will then rise through the upright pipes 7 to the box 8, whence it is deflected by the deflector 11 to the radiator 13, thence passing through the perforations 15 enters the room. As is obvious, a circulation will be established through said pipes and fresh air will be sucked through the funnel-shaped air-inlets into the pipe 5. Thus a supply of heated air will at all times be thrown out into the room.

Sufficient space is left between the upper edge of the asbestos backboard 16 and the rear face of the box 8 to admit of a draft up the chimney, which will draw all fumes and 5 prevent their escape into the room.

The pipes 5 and 7 may be, and are preferably, flattened somewhat, as shown, so as to occupy as little space as possible—that is, the pipe 5 is flattened so that its greatest diameter will be vertical and the pipes 7 so that 10 their greatest diameter will be horizontal. The elbows 6 are therefore flattened out at their extremities in substantially the manner shown in Figs. 5 and 6—that is, the opposite 15 ends of each elbow are flattened at right angles to each other.

I have shown my invention in what I consider to be its simplest form; but it is apparent that various minor changes may be made 20 in its construction without departing from the spirit or scope thereof. Hence I do not wish to limit myself to the precise construction shown and described.

Having thus described my invention, what 25 I claim as new, and desire to secure by Letters Patent, is—

1. In a hot-air heater for open grates, the combination with a gas-burner, of a horizontal pipe made up of telescopic sections and 30 provided with suitable air-inlets, said pipe located and suitably supported directly over said gas-burner, upright pipes composed of telescopic sections connected with said horizontal pipe, said upright pipes communicating 35 at their upper ends with the box and said box in turn communicating with a perforated radiator, substantially as described.

2. In a hot-air heater for open gas-grates, the combination with a gas-burner, of a horizontal pipe located directly over said gas-burner and provided with suitable air-inlets, 40 said pipe communicating at each end with an upright pipe, each upright pipe formed of telescopic sections and communicating with a 45 rectangular box, which in turn communicates with a perforated radiator, substantially as described.

3. In a hot-air heater, the combination with a gas-burner, of a pipe located horizontally 50 over said gas-burner and provided with funnel-shaped air-inlets, said horizontal pipe communicating at each end with a vertical pipe, each of said vertical pipes communicating 55 at its upper end with a suitably-supported box, a deflector in said box and a perforated radiator supported in front of said box in a position for receiving and distributing the heat passing upward through said vertical pipes, all of said pipes composed of two or 60 more sections adapted to telescope.

4. In a hot-air heater for open grates, the combination with a gas-burner, of a horizontal pipe located over said gas-burner, air-inlets communicating with said horizontal pipe, 65 a vertical pipe communicating with said horizontal pipe, all of said pipes formed of telescopic sections, and a radiator communicat-

ing with said vertical pipe, substantially as described.

5. In a hot-air heater for open grates, the 70 combination with a gas-burner, of a horizontal pipe located over said gas-burner, air-inlets communicating with said horizontal pipe, vertical pipes communicating with said horizontal pipe, a box communicating with said vertical pipes, a radiator communicating with said box, and a passage-way through which 75 the fumes escape, substantially as described.

6. In a hot-air heater for open grates, the combination with a gas-burner, of a horizontal 80 adjustable pipe located over said gas-burner, air-inlets communicating with said horizontal pipe, vertical adjustable pipes communicating with said horizontal pipe, a box communicating with said vertical pipes, 85 and a perforated radiator communicating with said box, substantially as described.

7. In a hot-air heater for open grates, the combination with a gas-burner, of a horizontal adjustable pipe located over said gas-burner, air-inlets communicating with said horizontal pipe, vertical pipes composed of 90 adjustable sections communicating with said horizontal pipe, an open box communicating with said vertical pipes, a heat-deflector seated 95 in said open box, and a perforated radiator suitably mounted in front of said box and communicating therewith, substantially as described.

8. In a hot-air heater for open grates, the 100 combination with a gas-burner, of a horizontal pipe located over said gas-burner, air-inlets communicating with said horizontal pipes, vertical pipes communicating with said horizontal pipe, all of said pipes formed of two 105 or more parts and arranged to telescope, and a perforated radiator communicating with said vertical pipes, substantially as described.

9. In a hot-air heater for open grates, the combination with a gas-burner, of a horizontal 110 pipe located over said gas-burner, funnel-shaped air-inlets communicating with said horizontal pipe, vertical pipes communicating with said horizontal pipe, all of said pipes formed of two or more sections and arranged to telescope, and radiating means 115 with which said vertical pipes communicate.

10. In a hot-air heater for open grates, the combination with a gas-burner of a horizontal 120 pipe arranged so as to be adjustable to grates of different widths and located over said gas-burner, vertical pipes communicating with said horizontal pipe and arranged so as to be adjustable to grates of different 125 heights, and radiating means with which said vertical pipes communicate, substantially as described.

Signed by me at Wheeling, West Virginia, this 23d day of February, 1903.

CHARLES FREDERICK BRAND.
